TOY AQUATIC SLED OR THE LIKE

Jack M. King, Huntington Beach, Calif., and William D. Stout, Provo, Utah, assignors to Mattel, Inc., Hawthorne, Calif., a corporation of Delaware

Filed Feb. 19, 1970, Ser. No. 21,521

Term of patent 14 years

Int. Cl. D21—02
U.S. Cl. D34—15

FIG. 1 is a perspective view of a toy aquatic sled showing our design;

FIG. 2 is a top plan view of same;

FIG. 3 is a right side view of same, the left side view being a mirror image thereof;

FIG. 4 is a front view of same;

FIG. 5 is a bottom view of same; and

FIG. 6 is a rear view of same.

We claim:

The ornamental design for a toy aquatic sled as shown and described.
